MOVABLE SUPPORT FOR CONES, CHEESES, OR THE LIKE

James Glenn Fisher, Hartwell, Ga., assignor to NVF
Company, Wilmington, Del.

Filed May 3, 1968, Ser. No. 11,781

Term of patent 14 years

U.S. Cl. D14—3
Int. Cl. D12—02

Fig. 2.

Fig. 4.

Fig. 3.

Fig. 4.

Fig. 5.
Fig. 6.

Fig. 7.

Fig. 8.

FIG. 1 is a front perspective view, showing my new design;

FIG. 2 is a left side elevation view of FIG. 1;

FIG. 3 is a perspective view of the rear left side of the support;

FIG. 4 is a top plan view of the support shown in FIG. 3;

FIG. 5 is a right side perspective view of a modified form thereof;

FIG. 6 is a left side elevation view of FIG. 5;

FIG. 7 is a perspective view of the rear left side of the support; and

FIG. 8 is a top plan view of the support shown in FIG. 7.

I claim:

The ornamental design for movable support for cones, cheeses, or the like, as shown and described.
